Inventor

S. B. Hill

United States Patent Office.

S. B. HILL, OF CHICOPEE, MASSACHUSETTS, ASSIGNOR TO HIMSELF, LEVI B. TAYLOR, AND CHARLES B. LANG, OF SAME PLACE.

Letters Patent No. 80,545, dated August 4, 1868; antedated July 18, 1868.

IMPROVED TASSEL-FASTENING.

The Schedule referred to in these Letters Patent and making part of the same.

TO ALL WHOM IT MAY CONCERN:

Be it known that I, S. B. HILL, of Chicopee, in the county of Hampden, and State of Massachusetts, have made and invented a new and useful Tassel-Fastening; and I do hereby declare that the following is a full, clear, and exact description of the construction and manner of using the same, reference being had to the annexed drawings, making a part of this specification, in which—

Figure 1 is a perspective view of the bobbin and cord,

Figure 2 a perspective view of the spring-fastening, and

Figure 3 a longitudinal section of the bobbin.

My invention relates to a tassel-fastening or device for hanging or attaching to cords such tassels as are formed around or constructed on wooden or other bobbins or core-blocks, and consists in making the hole through the bobbin *b* smaller at one end than at the other, and thus forming a shoulder, *e*, at any desirable point along the interior of the bobbin, but which shoulder I prefer to have near the upper end thereof, as seen in fig. 3.

And, further, I construct of brass or other suitable elastic wire or material, what I term the spring-fastening *a*, fig. 2, and I provide such fastening with one, two, or more coils at the top thereof, as a means of attaching the cord *c* thereto, and for the purpose of giving elasticity to the arms, the lower ends of which I bend or turn outward, thus forming hooks or projections intended to catch and fasten themselves on the shoulder *e*, and prevent the springs drawing out of the bobbin.

To hang tassels with my device, it is only necessary to tie a knot in the end of cord *c*, place such knotted end between the arms of spring *a*, and draw the cord upwards, when it will be formed between the wires forming the coil of such spring, the knot being within the coil; compress and insert the arms of spring *a* in the hole of bobbin *b*, and push such spring downward into the bobbin until the bent ends of the arms catch and fasten on the shoulder *e*.

To detach the tassel from the cord, push both the spring and cord by means of a small rod or stock, quite through the bobbin, when the spring *a* is readily removed, and the cord withdrawn.

It is manifest that the spring *a* may be formed with but one elastic arm; that but one arm need be bent, or have a hook formed at the end thereof; that instead of making the hole in one end of bobbin *b* larger than at the other, a groove may be formed in one or both sides of the interior of such bobbin; or finally, the hole through the bobbin *b* being all the way of a size, the spring-fastening *a* may be made a little longer than the bobbin, the bottom or lower end of which would then operate or serve the same purpose as the shoulder *e*, for the retention of the spring *a*; and in this last-mentioned manner my improved fastening may be readily applied to the common curtain-tassel found in the market.

But I consider all these variations substantially the same, and claim them as my invention.

Having thus described the construction and manner of using my fastening, what I claim as new, and for which I desire to secure Letters Patent, is—

Connecting the bobbin *b* and cord *c* by means of the spring *a*, substantially as described, and for the purpose specified.

S. B. HILL.
